Robert Malcom, Chicago, Ill., assignor to Chicago Eye Shield Company, a corporation of Illinois

Application November 22, 1941, Serial No. 420,151

5 Claims. (Cl. 2—14)

This invention relates to goggles to protect the eyes of persons engaged in industrial pursuits from intense light, dust, flying sparks, and other injurious substances, and also to goggles for general use.

Among the objects of the invention are to provide a wide-vision article of this class that includes protective lenses that are reliably held in place and yet are easily removable, after impairment for replacement by others, without use of a tool, one that can be worn over ordinary spectacles or other ophthalmic devices, and one that can be folded when not in use so that it can be carried in a garment pocket.

The invention also is directed to provision of a single means for retaining each lens in place and for attachment of a headband.

Further, the invention provides goggle frames or eyecups having ventilating vents so formed and positioned that dust is not apt to enter.

The eyecups of the goggles advantageously may be made of resinol or other suitable light and strong moldable material. Another object is to provide a goggle eyecup with parts so arranged and shaped that it can be molded easily by a two-part mold.

When considered with the description herein, characteristics of the invention are apparent in the accompanying drawings, forming part hereof, wherein adaptations are disclosed for purpose of illustration.

Like reference-characters refer to corresponding parts in the views of the drawings, of which—

Fig. 1 is a top view of a pair of goggles of a form provided by the invention;

Fig. 2 is a front view thereof, the lens and latch member being omitted from one of the goggles; Fig. 3 is an end view of a goggle;

Fig. 4 is a section on line 4—4, Fig. 2;

Fig. 5 is a section on line 5—5, Fig. 2;

Fig. 6 is a bottom view of the latch;

Fig. 7 is a view of the inner edge of the latch;

Fig. 8 is a view showing the latch loosened to permit removal and replacement of a lens;

Fig. 9 is an end view of the latch;

Fig. 10 is a view illustrative of another form of lens retaining member;

Fig. 11 is a section on line 11—11, Fig. 10;

Fig. 12 is a section on line 12—12, Fig. 11;

Fig. 13 is a view illustrative of an optional method of holding the latch in locked position.

Each eyecup is in the form of a frame consisting of upper and lower substantially parallel walls or members 14 and 15, respectively, having rear edges shaped to fit against the face around an

eye, and end members 16 and 17 connecting those walls. The frame is generally rectangular, except at the nasal end where the lower member 15 extends upwardly in inclined disposition and merges into the end member 16 to provide an end surface, as indicated by 18, to conform to and contact with the side of the wearer's nose. The eyecup appears as a rectangle with one corner omitted. The eyecup is arcuate in front—that is, it curves outwardly between the end members 16—17.

The upper and lower members of the frame are formed with inside oppositely disposed spaced flanges 19, the end member 16 has an inwardly extending flange 20, and these flanges have outer surfaces lying in the arc of a circle. The end member 16 has abutments 21 constituting stops. The upper and lower frame members also are formed, at or near their outer edges, with inwardly extending fingers 22, which are oppositely disposed and are positioned over the intervals between the flanges 19.

The under or inner surfaces of the fingers lie in the arc of a circle of greater diameter than that of the outer surfaces of the flanges 19, the difference being approximately that of the thickness of a curvilinear lens 23, which is slidable in the groove afforded by the flanges and fingers. The lens in plan corresponds to the inside shape and dimensions of the frame in which it is disposed. When in normal position, one end of the lens contacts the stops 21 of the end member 16. The other end of the lens then extends slightly over the end member 17 of the frame.

It is to be understood that, while the goggle glass is referred to as a lens, it is intended to denote any glass or other suitable transparent pane that may be used.

The inner sides of the frame members 14 and 15 have channels or grooves 24 extending inwardly from their outer edges between the fingers 22 to channels or grooves 25 in the flanges 19, these channels or grooves constituting ventilating vents between the edges and the under marginal surface of the lens. It has been found during use that vents so formed and located, while affording satisfactory ventilation to the inside of an eyecup, do not permit entry of appreciable amounts of dust thereto.

The lens is retained in place by a locking member or latch 26. When in locking position, its ends rest on the two flanges 19 at the juncture of the end frame member 17 with the upper and lower frame members 14—15, its inner edge 27 contacts with the end edge of the lens, and it

has an outer lip 28 that laps the outer marginal surface of the lens and inner lugs 29 that lap the inner marginal surface of the lens, the lip and lugs affording a groove in which the end of the lens seats.

The latch member 26 may be held in lock position with respect to the lens by a headband 30, preferably one of flat or tapelike flexible form having an enlarged end 31. The band is reeved and drawn through a slot 32 in the member 26 until stopped by the head 31, and the band also is disposed through a slot 33 in the end frame member 17. When the band is pulled through the slot 33 until the edge 27 of the member 26 is brought against or near to the edge of the lens, that member is in normal or lock position, and the end of the lens seats in the groove between the lip and lugs of the latch member.

Usually the headband is of rubber and of a size to resist its movement in the slot 33, with the result that the band holds the latch in lock position even when it is not under tension around the head of a wearer. However, if a tape, cord, or other elongated flexible article other than a headband is used to keep the latch locked, it may be tied, as shown in Fig. 13, or otherwise attached to the end frame member 17.

When a lens is to be removed, the latch member is pulled away from its normal position and enough of the headband through the slot 33 to free the lens and permit it to be withdrawn from the eyecup, as seen in Fig. 8; or, if a tied latch locking article is used, it may be untied to release the latch. With the latch unlocked, another lens may be inserted and the latch then drawn back to lock position.

Another form of lens lock is exemplified by Figs. 10 and 11. It comprises a substantially flat plate 34 held by a bolt 35 extending through the end frame member 17 and a finger nut 36. The parts are proportioned and arranged so that, when the nut is tightened against the plate, one outwardly flared edge 37 of the latter presses against an end of the lens. The plate has lugs 38 contactable with terminal fingers or flanges 39 of the frame member 17 to prevent rotary movement on the bolt. The plate has a slot 40 or other suitable opening therethrough in its outer end for connection of a headband thereto.

When a lens is to be removed, the nut is turned on the bolt enough to loosen the plate from the lens to the extent required for its withdrawal; and, after another lens has been inserted into the eyecup, the plate is tightened to lock position.

Two of the eyecups of the invention may be connected as a pair of goggles in any suitable

manner. For example, as seen in Fig. 2, they may be connected by a bridge band 41, which passes around the end frame member 16; or, as seen in Fig. 11, a headed bridge member 42 may be disposed through an opening 43 in the nasal end of each eyecup.

I claim:

1. A goggle comprising a frame of substantially parallel side members connected by end members, 10 opposite flanges on the inside of said side members, fingers extending inwardly on said side members, a stop at one end of said frame and there being an opening in the other end thereof, a lens slideable between said flanges and fingers to said stop, a latch, an elongated flexible member disposed through said opening, connected to said latch, and normally holding the latter locked with respect to said lens.

2. A goggle comprising a frame of substantially parallel side members connected by end members, 20 opposite flanges on the inside of said side members, fingers extending inwardly on said side members, a lens slideable into and out of said frame between said flanges and fingers, and releasable means to hold said lens in said frame, 25 there being ventilating vents between said fingers in said side members and flanges adjacent to the edge and under marginal surface of said lens.

3. A goggle comprising a frame, a lens slideable 30 into and out of said frame, a latch bodily and slidably movable substantially in the same plane as said lens toward and from an edge thereof, and an elongated flexible article connected with said latch and holding it in lock position adjacent to said lens edge.

4. A goggle comprising a frame of substantially parallel side members connected by end members, 35 spaced flanges on the inside of said side members, fingers extending inwardly on said side members, 40 members over the spaces between said flanges, a lens slideable to and from normal position between said flanges and fingers, and releasable means to hold said lens in normal position, there being ventilating channels extending inwardly in 45 the walls of said side members between said fingers past edges of said lens and in said flanges under the marginal surface of said lens.

5. A goggle comprising a frame, a lens slideable 50 into and out of said frame, a latch bodily movable substantially in the same plane as said lens toward and from an edge thereof, and an elongated flexible article connected with said latch and operable to pull the latter toward and to hold it against said edge.

ROBERT MALCOM.
